UNITED STATES PATENT OFFICE

165,926

FLOOR MAT

Dudley W. Moor, Jr., Toledo, Ohio, assignor to American Mat Corporation, Toledo, Ohio, a corporation of Delaware

Application February 1, 1951, Serial No. 14,065

Term of patent 14 years

(Cl. D9—6)

To all whom it may concern:

Be it known that I, Dudley W. Moor, Jr., a citizen of the United States, residing at Toledo, in the county of Lucas, State of Ohio, have invented a new, original, and ornamental Design for a Floor Mat, of which the following is a specification, reference being had to the accompanying drawing, forming a part hereof.

Fig. 1 is a top view of a floor mat, showing my new design.

Fig. 2 is a bottom view of the floor mat shown in Fig. 1.

Fig. 3 is a detailed sectional view taken on the line 3—3 of Fig. 1.

Fig. 4 is a fragmentary view in elevation indicated by the line 4—4 of Fig. 5.

Fig. 5 is a fragmentary enlarged perspective view of one corner of the mat shown in Fig. 1.

I claim:

The ornamental design for a floor mat, as shown.

DUDLEY W. MOOR, JR.
